UNITED STATES PATENT OFFICE

JOHN HENRY HILLS, OF GRAND RAPIDS, MICHIGAN, ASSIGNOR TO BOUSMAN MFG. CO.,
A CORPORATION OF MICHIGAN

VACUUM STILL

Application filed September 6, 1928. Serial No. 304,245.

This invention relates to distilling apparatus operated under a partial vacuum to reduce the temperature required for distilling the liquid being treated. As a particular embodiment of this invention, a hydrocarbon still such as is used to purify dry cleaning agents has been selected for illustrative purposes.

Heretofore, such vacuum distilling apparatus has comprised a closed still having means for heating the same and means for agitating the liquid therein, the still being connected to a cooling condenser for the gases driven off from the liquid by the heating thereof, together with a vacuum pump for removing non-condensed vapors and air from the condenser and still. To commence the operation of such a distilling apparatus, a vacuum must first be produced, and to depend upon a vacuum pump to exhaust the air from the still and condenser would involve considerable delay even though the pump were several times as large as required for maintaining the desired vacuum, when once established.

It is accordingly an object of this invention to provide an inexpensive and reliable means for quickly establishing a desired degree of vacuum. In order to accomplish this result, I provide a steam nozzle for introducing steam into the space above the liquid in the still and introduce sufficient steam to drive or displace the air out of the still and condenser. The condenser promptly acts to condense this steam to water, thus producing an initial vacuum which can then be maintained by a relatively small vacuum pump which would otherwise be inadequate to produce the initial vacuum within a reasonable time. An advantage of my invention lies in the coaction of the steam with the condenser after the steam has displaced the air initially in the system, thus economizing in size of vacuum pump required as well as effecting a substantial saving of time required for starting.

It is also an object of this invention to provide a method for producing a vacuum that can utilize the normal steam supply required for heating and agitating the liquid in the

steam, thus reducing the cost of building and installing a vacuum distilling apparatus.

Other and further important objects of this invention will be apparent from the disclosures in the specification and the accompanying drawing.

This invention (in a preferred form) is illustrated in the drawing and hereinafter more fully described.

On the drawing:

The single figure is a vertical section through a vacuum distilling apparatus embodying the features of this invention.

As shown on the drawing:

The still proper comprises a cylindrical vessel 10 having a removable cover 11 bolted to a flange 12 on the shell 10 and a removable double bottom 13 and 14 defining a steam space 15 therebetween with a steam connection 16 thereto. A drain valve 17 is connected to a pipe 18 extending through both bottoms. A steam coil 19 may be mounted within the still in addition to the steam space 15.

Means for agitating the contents of the still are provided comprising a steam connection 20 leading to an ejector type of nozzle 21, the flow of steam drawing liquid from the still into the nozzle 21 through a series of holes 22 to increase the agitating effect of the entering steam.

An outlet pipe 23 for distilled vapor is provided in the cover 11 and leads to a condenser 24 of any suitable type, which in turn is connected to a vacuum pump 25.

A device for accomplishing the method of the present invention comprises a steam supply pipe 26 having a valve 27 and leading to a depending nozzle 28 positioned above the level of the liquid 29 in the still. An inverted conical baffle 30 is suspended in spaced relationship to the cover 11 by braces 31 and serves to cause a flow of gases and steam up along the walls of the still, any moisture condensing on the baffle draining back to the still through a hole 32 in the tip of the cone.

The method of the present invention comprises initially establishing a vacuum by displacing the air and non-condensable gases in the upper part of the still and condenser by introducing steam which acts to displace the

air, driving the air ahead of the steam and out through the vacuum pump. The condenser in turn acts upon the steam to reduce it to water so that in conjunction with the 5 vacuum pump the condenser can quickly produce the desired degree of vacuum after introducing sufficient steam to fill the gaseous spaces in the still and condenser.

It will thus be seen that I have invented 10 an improved method for quickly establishing a desired degree of vacuum in a still which reduces the capacity of the vacuum pump required and also materially reduces the time required to place the still in operation.

15 I am aware that many changes may be made, and numerous details of construction may be varied through a wide range without departing from the principles of this invention, and I therefore do not purpose limiting the patent granted hereon, otherwise than necessitated by the prior art.

I claim as my invention:

20 A vacuum still comprising a closed vessel normally partially filled with a liquid thereby defining a vapor space above said liquid, a condenser, a vacuum pump for said condenser, a conduit connecting said condenser and said vessel above said liquid to carry 25 vapor from the vapor space, means to heat said liquid for normal operation of said still, and means to initially remove air from the vapor space when the liquid is below normal operating temperature, said means comprising 30 a nozzle positioned in the vessel intermediate the liquid and the conduit connection to eject steam angularly against the surface of the liquid whereby air and steam are passed through said condenser to produce an 35 initial vacuum in the still.

40 In testimony whereof I have hereunto subscribed my name at Grand Rapids, Kent County, Michigan.
